UNITED STATES PATENT OFFICE.

EMIL G. NELSON AND JOHN LANDECK, OF WHAT CHEER, IOWA.

CONSTRUCTION-BLOCK.

1,278,194.

Specification of Letters Patent. Patented Sept. 10, 1918.

Application filed May 8, 1916. Serial No. 96,214.

To all whom it may concern:

Be it known that we, EMIL G. NELSON and JOHN LANDECK, both of whom are citizens of the United States, residing at What 5 Cheer, in the county of Keokuk and State of Iowa, have jointly invented certain new and useful Improvements in Construction-Blocks, of which the following is a full, clear, concise, and exact description, reference being had to the accompanying drawings, forming a part of this specification.

Our invention relates to construction blocks, and more specifically to blocks of burnt earthenware for building up hollow 15 cylindrical or tubular structures such as sewers, drains, silos, etc.

Among the objects of our invention is to provide an improved construction block such that a structure built up of these blocks 20 would have no continuous longitudinal joint, and such that a conduit constructed of these blocks may be laid up without forms and without back filling until the entire conduit has been laid and accepted by the engineer.

25 In the drawings, in which one embodiment of our invention is shown;

Figure 1 is an end view of a hollow cylindrical structure built up of interlocking blocks;

30 Fig. 2 is a side elevation of the structure; Fig. 3 is a perspective view of one of the blocks; and

Fig. 4 is a view of the edge of the block.

Referring to the drawings in detail the 35 cylindrical structure 10 is built up of blocks 11 which are exactly alike with the exception of those at the beginning and end of the structure which must be formed specially in order to bring the edges of the blocks 40 flush with each other at these points.

Each of the blocks 11 is curved to conform to the diameter of the structure which is to be built up and is made hollow being provided with two longitudinal passages 12 and 13. The block has two longitudinally extending ribs 14 extending within the passage 13 the purpose of which will appear hereinafter. One edge of the block is provided with a tongue 15 which forms a dove-tailed joint with a groove 16 at the edge of an adjacent block. The block is cut away along the lines 17 and 18 to form a reentrant angle to receive the corner of an adjacent block. This construction results in breaking 55 the joints both longitudinally and trans-

versely so that there is no continuous joint either longitudinally or transversely.

Another edge portion of the block is provided with tapering tongues 19 and 20 which engage a corresponding groove 22 in an adjacent block to properly position the blocks with respect to each other and hold them in position. The block is cut away on the line 18 so as to leave a groove 23 along this edge, the walls of which are a continuation of the 60 walls of the passage 13 and this groove 23 receives a correspondingly shaped tongue on the edge of an adjacent block. These blocks may be shaped by forcing the material, preferably a clay or clay mixture, in a plastic 65 state out through forming plates which give to the block its transverse section, and these blocks may then be vitrified if desired.

In building up the structure the blocks are placed in position by placing the tongue 75 15 in position to enter the groove 16 of the block already in position and sliding the block into position longitudinally until the tongues 19, 20 enter the groove 22.

By breaking the joints longitudinally the 80 weakness of a structure which has a continuous longitudinal joint is avoided, as such structures are likely to fail along the line of the longitudinal joint.

Referring to Fig. 2 it will be noted that 85 there are two blocks interposed longitudinally between blocks having their edges in alinement.

Because of the dove-tail connection between adjacent blocks and the breaking of 90 the joints longitudinally a conduit of these blocks can be built up without forms and without back filling until the entire conduit has been laid up and inspected.

Having thus described our invention what 95 we claim as new and desire to secure by Letters Patent is;—

1. A construction block having an edge having a reentrant angle to receive the corner of an adjacent block, the edge along one 100 leg of said reentrant angle being grooved to receive the tongue of an adjacent block, said block having a longitudinally extending passage therethrough, the walls of said groove being continuous with the walls of 105 said passage.

2. A construction block having a reentrant angle on one end, the upper leg of said angle having a tongue and the lower leg being grooved, the said block having a passage 110

extending therethrough, the walls of said passage being continuous with the walls of said groove, the said block having a continuous groove on its opposite end and uppermost side and being provided with a continuous tongue on its lowermost side and end adjacent said angle, the tongue on the end

adjacent said angle having a passage extending longitudinally through the said block. 10

In witness whereof, we have hereunto subscribed our names.

EMIL G. NELSON.
JOHN LANDECK.
